MAGAZINE DOOR ASSEMBLY

William M. Magers, Coon Rapids, and Palmer G. Wermager, Minneapolis, Minn., assignors, by mesne assignments, to the United States of America as represented by the Secretary of the Navy

Filed Aug. 30, 1961, Ser. No. 136,691

1 Claim. (Cl. 292—144)

The present invention relates generally to door assemblies and closures therefor, and more particularly it pertains to an armament magazine hatchway door assembly having a locking system of high integrity.

Door assemblies of this type are used in rugged service usually on shipboard and are required to be watertight, flametight, and capable of remaining closed under great gas pressure in the event of a magazine fire. Further, the exigencies of modern armament dictate rapid opening and closing times and mechanism which is adaptable to automation. Because of the great length of the doors, in the range of thirty feet or more, the latching means must be distributed uniformly to preserve the seal when the doors are closed.

In the light of the foregoing, it is an object of the present invention to provide means for safety latching greatly elongated doors so they will withstand high internal pressure and temperature without leaking.

Another object of this invention is to provide a hydraulically operated, automatically sequenced, series of safety and cam latches and door actuators for opening and securely closing fluid tight doors.

Still another object of the present invention is to provide a deck-mounted fixed actuator for a movable door mounted safety latch.

And yet another object of this invention is to provide door-closed hydraulically operated cams for magazine doors.

Still another object is to provide a door assembly having a system of hydraulically actuated latches and cams for securely locking door members of said assembly in their opened or closed positions.

Other objects and many of the attendant advantages of this invention will be readily appreciated as the same becomes better understood by reference to the following detailed description when considered in connection with the accompanying drawings wherein:

FIG. 1 is a dimetric view of a magazine door assembly used in connection with a missile feeder system, partly broken to foreshorten the depiction thereof;

FIG. 2 is a cross-section of the magazine door assembly taken along the line 2—2 of FIG. 1;

FIG. 3 is an enlarged detail cross-section of the magazine doors taken along the lines 3—3 of FIG. 1;

FIG. 4 is a greatly enlarged plan view of a section of the safety latch;

FIG. 4A is an exploded view of the safety latch section shown in FIG. 4;

FIG. 5 is a hydraulic schematic of safety and cam latch actuators with the magazine doors closed;

FIG. 6 is a hydraulic schematic of the overall magazine door arrangement showing the magazine doors opened;

FIG. 7 is a generally diagrammatic plane view of the door latch bar assembly in the released or open condition thereof and

FIG. 8 is a view similar to FIG. 7, showing the latch bar assembly in the closed or latched condition thereof.

Referring now to FIGS. 1, 2, and 3 of the drawings, there is shown therein a pair of magazine doors 10 and 18 arranged in double-swing-door fashion and hinged so as to come into side contact when closed. The left door 10 is provided at its inboard edge with a continuous rigid

2

latch bar assembly 12, which comprises the movable portion of the zipper-type latching means.

This latch bar assembly 12 is arranged to slide longitudinally for a short distance along the edge of its door 10 and it carries, at spaced intervals, a plurality of latching hooks 14 which cooperate with a series of notched latching blocks 16 that are arranged at spaced intervals along the inboard edge of the right door 18.

As best shown in FIGS. 3, 4, and 4A the latch bar assembly 12 comprises a continuous elongated bar 20 having raised portions 26 and longitudinally elongated slots 30 extending alternately along its entire length. When bar 20 is mounted along the inboard edge of door 10 the raised portions 26 define slots 21 (FIG. 4A) which receive the tongue portions 27 of latching hooks 14, the tongue portions being anchored within said slots 21 by means of cap screws 28. The elongated slots 30 interspersed between raised portions 26 receive reduced portions 32 (FIG. 3) of guide and retainer blocks 34, which blocks seat upon hardened slide plates 36, said blocks and slide plates being fixedly secured to the inboard edge of door 10 by means of cap screws 38.

As best seen in FIG. 3, the guide and retainer blocks 34 are substantially T-shaped in cross-section and are of such dimension as to allow sliding action of the slotted portions of bar 20 between the hardened slide plates 36 and the head portion of said guide and retainer blocks 34. These slide plates and their associated slots 30 are so designed as to maintain the alignment of the latch bar assembly 12 with respect to the edge of door 10 while permitting reciprocating longitudinal movement of bar 20 through a stroke of approximately one to three inches when said bar is actuated to engage or disengage latching hooks 14 from notched latchway blocks 16. It should be noted that slide plates 36 have the additional function of assisting in retaining an edge gasket 40 positioned in a notch 42 at the edge of the door 10, as best depicted in FIG. 3.

The latching hooks 14 are each formed with a cut-away corner 44 which longitudinally houses a semi-cylindrical hardened key or insert 45. The notched latchway blocks 16, which are fastened close to the edge of the door 18 by cap screws 48, are provided with a hardened groove or notch 50 so located as to receive the key 45 in close fitting relationship when the latch bar assembly 12 is shifted lengthwise, thereby securely latching together the doors 10 and 18. The portions of the door 18 between the notched latchway blocks 16 are provided with straps 52 secured by cap screws 54 (FIG. 4). These straps 52 serve to retain a gasket 56 within a corner notch 58 along the edge of door 18.

All around the inner edge of the hatch frame 60, there is provided a gasket 62 which is compressed by the under surface of the doors 10 and 18 when they swing down on their hinges 64.

When the doors 10 and 18 are closed, bar 20 of the latch bar assembly 12 becomes drivingly engaged with hooked piston rod 72 of a deck mounted actuating piston 70 by means of an actuating shaft 66, as shown best in FIGS. 5 to 8. It is the function of the piston 70 to pull upon this actuating shaft 66 and cause the latching hooks 14 to engage with the notched latchway blocks 16.

During the first portion of the travel of the actuating shaft 66, a spring-held detent 68 is cammed against its spring 74 into its disengaged or release position, whereby the pointed end of detent 68 registers with notch 69 in bar 20 and then with continued movement of rod 72 to the right, as viewed in FIGS. 7 and 8, bar assembly 20 is urged to the right forcing latching hooks 14 into locking engagement with notched latchway blocks 16.

In the unlocked condition, as shown in FIG. 5 and when the doors 10 and 18 are open as shown in FIG. 6,

the latch detent 68 butts against the end of the latch bar assembly 12 and prevents it from accidentally being displaced by vibration or shock into other than a fully opened or unlocked position.

In addition to the safety latching means just described, the doors 10 and 18 have a pair of door-closed locking cams 76, shown in an unlatched condition in FIGS. 5 and 6. These locking cams 76 cooperate with latch fingers 78 which are provided with rollers 110 at the latched or engaged end 111 thereof and fixed at the opposite ends thereof on the inside surfaces respectively of the doors 10 and 18. Each locking cam 76 functions in a manner similar to a turn button and operates by being rotated through one quarter revolution by a vertical shaft 80 connected thereto. The shaft 80 is attached to and driven at its lower end by a gear sector 82 which meshes with a rack which is integral with hydraulic piston 84.

A door-open latch cam 86 is fastened to the under-side of the door 10 to prevent inadvertent closing of the magazine doors. A spring-loaded bell crank 90 having a roller tip 88 bears against this cam 86 and engages a detent notch 92 thereon when the doors 10 and 18 are fully opened. When the doors 10 and 18 are to be closed, a piston 94 is actuated to move the bell crank 90 clockwise, as viewed in FIG. 6, to disengage the roller tip 88 from the notch 92.

The doors 10 and 18 are opened and closed by a door operating piston 96. The upper end of the piston 96 is fastened to a guide 98 which runs on tracks 100 as best shown in FIG. 2. This guide 98 is connected to a pair of pivoted links 102 which push or pull upon the magazine doors 10 and 18 to open and close same.

In operation, beginning with the doors 10, 18 in their closed position, piston racks 84 are hydraulically actuated to rotate shafts 80 and their associated cams 76 through approximately a one-quarter turn to release latch fingers 78. Simultaneously, piston 70 is hydraulically actuated through an extend stroke, forcing actuating shaft 66, and consequently bar 20, to latch unlocked position, whereupon detent 68 is freed to be returned by spring 74 to engage and hold bar 20 in its latch-open position. Piston 96 is then actuated to swing doors 10, 18 upwardly and outwardly into their open position through operation of track-mounted guide 98 and links 102. As door 10 is swung into its fully opened position, roller-tipped, spring-biased bell crank 90 engages the notch 92 in door-open latch cam 86 to lock door 10 and, by virtue of interconnecting linkage 98, 102, door 18 in their fully opened positions. When it is desired to close the doors, piston 94 is hydraulically actuated to rotate bell

crank 90 in a counter-clockwise direction, as viewed in FIGS. 5 and 6, to disengage roller tip 88 from notch 92, whereupon doors 10, 18 are free to close by actuation of piston 96 through a retract stroke. The door-locking sequence is the reverse of that above related as to the door-opening sequence.

Obviously many modifications and variations of the present invention are possible in light of the above teachings. It is, therefore, to be understood that within the scope of the appended claim the invention may be practiced otherwise than as specifically described.

What is claimed is:

A latching mechanism for a pair of hinged doors meeting along their inner edges in sealing relationship comprising: an elongated bar mounted for relative reciprocal linear movement on the surface of one door and adjacent to its meeting edge, said bar being alternately formed with raised portions and slotted portions, said raised portions forming a slot with the door surface; a plurality of latching hooks adjustably mounted in the slot formed of the bar and the door surface; semi-cylindrical inserts mounted on each of said latching hooks; insert receiving blocks mounted on the other of said doors and in such a relation as to receive the insert of the latching hooks in tight engagement; hydraulically operated means engaging the elongated bar to move it longitudinally into or out of locking position; said hydraulically operating means being in actuating position when the doors are closed and completely free of the latching mechanism when the doors are open; and a safety means engaging the latching mechanism when said latching mechanism is in open position to retain the latching mechanism in open position, said safety means being released by the hydraulically operated means prior to the latching operation.
